K. H. CARPER.
SPARK CONDUCTOR.

No. 398,818

Patented Mar. 5, 1889.

UNITED STATES PATENT OFFICE.

KENT HERSEY CARPER, OF SALEM, VIRGINIA.

SPARK-CONDUCTOR.

SPECIFICATION forming part of Letters Patent No. 398,818, dated March 5, 1889.

Application filed December 7, 1888. Serial No. 292,899. (No model.)

To all whom it may concern:

Be it known that I, KENT HERSEY CARPER, a citizen of the United States, residing at Salem, in the county of Roanoke and State of Virginia, have invented new and useful Improvements in Spark-Conductors, of which the following is a specification.

The invention relates to improvements in spark-conductors.

10 The object of the present invention is to provide a spark-conductor of simple and comparative inexpensive construction that will in a positive and reliable manner convey the smoke and sparks and cinders from a locomotive and deposit them in suitable places and prevent them entering the cars or setting afire the adjacent property.

15 The invention consists in the novel construction, combination, and arrangement of the parts hereinafter fully described and illustrated in the accompanying drawings, and pointed out in the claims hereto appended.

20 In the accompanying drawings, Figure 1 is a side elevation of a train of cars provided with the improved spark-conductor. Fig. 2 is a vertical central sectional view of the spark-conductor and a portion of the smoke-stack disconnected. Fig. 3 is a detail view of one of the end supports of the flue. Fig. 4 is a 25 cross-section taken on line xx of Fig. 2. Fig. 5 is a detail sectional view of the spark-receptacle; and Fig. 6 is a side elevation, partly in section, of the central support.

25 Referring to the accompanying drawings, A designates a locomotive having its smoke-stack a provided at the top and on its front side with a flaring mouth, a' , whereby a direct draft is caused through a flue, B, which conveys the smoke and some of the sparks 30 from the locomotive A to the rear of a train of cars, C.

35 The draft through the flue B is regulated and controlled by a damper, a^2 , which is hinged to the top of the stack and opens and closes 40 the top of the smoke-stack a , and consequently the passage through the flue B, and it has attached to it a rope or other suitable connecting means, which extends to the cab of the locomotive and within easy reach of the engineer and fireman. By this construction a 45 straight draft out of the smoke-stack can be

caused when the locomotive is backing or switching.

The section B' of the flue B, passing over and attached to the locomotive and the tender 55 A', consists of a single tube, which has its forward end, b , suitably connected to smoke-stack a . This forward end, b , is bell-mouthed, and its lower side has connected to it a discharge-tube, D, which extends down below the 60 boiler of the locomotive A, and is provided at its lower end with a weighted valve, d . The smoke and other products of combustion, after leaving the smoke-stack a , impinge against the inclined damper a^2 , and are deflected and 65 thrown against the bottom of the bell-mouthed end b , thereby causing a great portion of the cinders and sparks to fall into the discharge-tube D. The upper end of the discharge-tube 70 D is flaring and readily receives the sparks, while the lower end is provided with the weighted valve d . The weighted valve d consists of a damper and a weighted lever to control the damper, and the valve may be regulated by diminishing and increasing the weight 75 to hold any desired amount of cinders before opening.

The flue B has a number of discharge-tubes, D, constructed similarly to the one described, and all of the weighted valves d may be connected by a rope or the like, which may be under the control of the conductor or engineer, who may empty the discharge-tubes D while the cars are crossing water or other suitable places. The discharge-tube D, instead of being arranged to deposit the cinders at intervals along the route, may have enlarged ends of sufficient capacity to contain the cinders given off during the entire trip. 85

The section B' of the flue B is connected to 90 and held above the locomotive by supports E, composed of a tripod base, e , and a clamp, e' , consisting of a curved piece suitably secured to the base e , and curved arms hinged to the curved piece and completing a circle when 95 closed, which surrounds and securely clasps the flue B. One of the curved arms of the clamp e is provided with a hook, and the other has a link to be engaged by the hook to fasten the two parts together. 100

Just back of the smoke-stack a the section B' of the flue has extending a considerable

distance of its length a wire-gauze or similar bottom, b' , under which is placed a metal trough, b^2 , having its rear end connected to and communicating with a discharge-tube, D, 5 similar to the one above described. The products of combustion passing through the flue B deposit upon the wire-gauze bottom b' a large amount of sparks and cinders, which drop into the trough b^2 , and are then conveyed into the discharge-tube D and disposed of in the manner heretofore described.

At various intervals along the section B', and also along the entire flue B, are branch tubes b^3 , slightly inclined in the direction of 15 the draft and re-enforcing the same. These branch tubes b^3 have flaring mouths and permit access to the various parts of the flue B for cleaning or the like. The section B', which passes over the locomotive and tender, 20 is connected to a section, B², by passing a considerable distance into a bell-mouthed end, b^4 , whereby when the cars are passing around curves the sections of the flues will have great freedom of movement without liability of 25 parting or permitting the exit of the products of combustion. The section B² is of a length equal to the length of a car, and is secured thereto intermediate of its ends by a central support, E', the clamp e' of which is swiveled 30 to the base e, whereby the section B² is rendered capable of rotation to bring the bell-mouthed end b^4 at either end of the car. This central support, E', has the clamp e' , secured to a screw, e^2 , which engages an internally-threaded cup, e^3 , that is inserted in a collar, e^4 , connecting the legs of the tripod base e. Besides the central support, the section B² is 35 secured at the ends of the car, and at suitable intervening points, if desired, by the end 40 supports, E, constructed as heretofore described. When it is desired to change the bell-mouthed end of the section B² from one end of the car to the other, the curved arms of all the clamps e' , except the central one, are 45 unfastened, and then the section B² is turned upon its central support and secured in position by the clamps e' .

Each of the sections B² is provided with a wire bottom, b, and a trough, b^2 , of a construction already described. The trough b^2 terminates in a spout, b, which projects into a funnel-shaped mouth, d' , of the upper end of the discharge-tubes D, that are placed at the middle of the cars, and when the section B² is 55 swung around the spout b^5 does not leave the funnel-shaped mouth d' . The sections B² are placed upon all the cars, and the rear one has suitably secured to it a receptacle, F, constructed of wire-gauze, which will permit passage of the smoke, but will retain the sparks 60

and cinders. The floor f of the receptacle F is an automatic door held normally closed by a spring, G, but which will open against the tension of the spring G when a sufficient amount of cinders have collected. The spark-extension F has a cylindrical extension, f', which fits snugly on the flue B at an end of a section B², thereby rendering the spark-receptacle readily removable from the section B², to facilitate its being conveniently placed 65 at the end of the train of cars.

When the spark-conductor is designed to be employed in connection with freight-trains, the flue B extends only to the rear of the tender, and is provided at its terminus with 70 a suction-fan suitably connected to and operated by the engine, and does not have the inclined branch tubes to re-enforce the draft.

From the foregoing it will be readily seen that spark-conductors as above described will 75 convey the smoke, sparks, and cinders of the locomotive away from the passengers, and successfully prevent their setting fire to the neighboring buildings and other property.

Having described the invention, what I 80 claim is—

1. In a spark-conductor, the flue provided with the branch tubes extending out from the conductor and slightly inclined in the direction of the draft to re-enforce the same, and 85 provided with flaring or bell-shaped mouths, substantially as described.

2. In a spark-conductor having a flue and discharge-pipes suitably connected thereto and placed at suitable distances along said 90 flue, and provided at their lower ends with weighted valves controlled as described.

3. A spark-conductor having the flue provided with the wire-gauze bottom and the trough secured beneath said gauze bottom, 95 substantially as described.

4. A spark-conductor having a reversible flue-section provided with a central support having a swiveled clamp, and the end supports provided with curved clamping-arms 100 hinged to the base, substantially as described.

5. In a spark-conductor, the wire-gauze receptacle detachably connected to the rear end of the flue and having its bottom constructed of gauze and hinged to one of its sides and held normally closed by a spring, substantially as described.

In testimony that I claim the foregoing as my own I have hereto affixed my signature in presence of two witnesses.

KENT HERSEY CARPER.
